UNITED STATES PATENT OFFICE.

LOUIS L. CLAXTON, OF PATERSON, NEW JERSEY.

THERMOSTAT.

986,801.

Specification of Letters Patent. Patented Mar. 14, 1911.

Application filed December 13, 1907. Serial No. 406,353.

To all whom it may concern:

Be it known that I, LOUIS L. CLAXTON, a citizen of the United States, and resident of Paterson, in the county of Passaic and State 5 of New Jersey, have invented certain new and useful Improvements in Thermostats, of which the following is a specification.

This invention relates to a mechanical device for the controlling of heat in incubators 10 and brooders and also for the operating of valves or devices by means of which heat is controlled.

The object of this invention is to secure a greater movement than any other similar 15 device known, this increase of movement is secured by taking advantage of the difference in the co-efficient of expansion of different metals, which movement is greatly increased by compelling same to take a radial 20 dial course around the center point of the bar having the lesser expansion instead of permitting same to move in a perpendicular direction through points at each end which would greatly reduce the movement, all of 25 which is more particularly described and claimed below.

In the drawings forming a part of this specification, Figure 1 is a front view of my invention. Fig. 2 shows the radial action 30 of the thermostat and its position on an increased degree of heat. Fig. 3 is a cross section through the center on a line of rod *e* of Fig. 1. Fig. 4 is a detail of the 35 section made beside the rivet *i* at the end of the bars. Fig. 5 is an end view of a cross section made beside the rivet *i* at the end of the bars. Fig. 6 is a detail of the two lower 40 bars. Fig. 7 shows a number of devices connected for the purpose of increasing the length of movement.

In the drawings, similar letters refer to 45 similar parts throughout the several views.

In the drawing a bar *a* and *d* of metal are represented as being the most sensitive to the action of heat, and the intermediate bar 50 *c* as one the least sensitive to heat. The bar *a* consists of a metal plate with flanged sides to make it rigid and also to keep it from curving when expanding, so that the action will be lengthwise the bar, and has 55 its flanges cut out at points indicated by *b* on each side at its center and near its ends; this is so that the web or flat portion can bend when necessary, and act as a hinge. All the points of cutting the flanges are not 60 necessarily cut out where indicated, but may be at other points in the flanges where found

necessary. The intermediate bar *c* is also made of similar construction as the bars *a* and *d* except as to cutting flanges but consists of some metal which is less expansive 60 when heated, the three are secured at their ends to each other by rivets *i*, these rivets are inserted between the extreme ends and the places where the flanges are cut as shown in Fig. 1. The intermediate bar *c* 65 and the bar *d* are rigidly secured between their ends, the bar *c* lying in closer proximity to the bar *d* than to the bar *a*, the fastening is made by means of the piece *h*, through which the rivets *i* also pass. This 70 bar *c* can be attached to *a* with the same results instead of the bar *d*. The intermediate bar *c* having the lesser expansion can either be straight or bowed toward the bar to which it is strapped at the center. The bars which 75 are strapped at their center are secured with plates *s* and *x* above and below in addition to the piece *h*, with rivets, the single bar also has a piece *s* below it at the center secured with rivets, to make them more rigid. 80 The part *f* is secured to the upper bar by means of rivets and in this is secured a pipe or tube *g*, and through this pipe the rod *e* passes freely, it is by means of this pipe *g* that the instrument is held in position. The 85 rod *e* passes freely through the upper bar and fittings, also through the flat strap *s* on the top bar, also through the plate *s* on the bar *c*, through the bar *c* the piece *h* and the bar *d*, and in the plate *x* there is a thread 90 tapped which receives the threaded lower end *l* of the rod *e* in this piece *x* is the only connection between the rod *e* and the device. There is also a lock nut *m* screwed on the threaded end *l* of the rod *e* to secure it 95 in an adjusted position. In each bar the flanges must be so that they will not rub, that is the outside one is the widest bar and the others fit freely between the flanges as shown in Fig. 5.

In more fully describing the movement of the device as shown in Fig. 2, the dotted line *j z* is the line of bar *a* in the expanded position, the dotted line *w z* is the line of *c* showing a less expansion than the line of *a*, 105 the arc of the dotted line *w z* is in the arc *n n* and the arc of the dotted line *j z* is in the arc *k k*, and *z* is the point of intersection indicating the position of the ends of the bars *a* and *d* and *c* when expanded. The line *j o* is a perpendicular line through the center of the device and *o* is the point of inter- 110

- section of the lines o_2 which is the line of the bar d in an expanded position in the perpendicular o_j , o is therefore the extreme bottom point of the device when expanded.
- 5 By compelling bar a to expand around w the center of bar c , which has a lesser expansion than the bar a , it will draw the extreme ends of the device closer together and at the same time produce an increased
- 10 downward movement.

Having thus described my invention what I claim and desire to secure by Letters Patent is—

15 A compound thermostat adapted to transmit motion radially with respect thereto,

comprising three bars having their ends joined together, the intermediate bar having a less coefficient of expansion than the outer bars, said intermediate bar being rigidly secured between its ends to one of said outer bars and lying in closer proximity thereto than to the other outer bar as set forth and described.

Signed at Paterson in the county of Passaic and State of New Jersey this 26th day 20
of Nov. A. D. 1907.

LOUIS L. CLAXTON.
